DESIGN FOR A SUSPENDER CLASP OR SIMILAR ARTICLE

Michael Glaser, Washington, D. C.

Application August 27, 1942, Serial No. 108,047

Term of patent 3½ years

To all whom it may concern:

Be it known that I, Michael Glaser, a citizen of the Polish State, residing at 151 East 83d Street, New York, in the State of New York, have invented a new, original, and ornamental Design for a Suspender Clasp or Similar Article, of which the following is a specification, reference being had to the accompanying drawing, forming part thereof.

Fig. 1 is an enlarged front view of a suspender clasp or similar article showing my new design;

Fig. 2 is an enlarged rear view of the clasp shown in Fig. 1;

Fig. 3 is an enlarged side view of the clasp shown in Figs. 1 and 2.

I claim:

The ornamental design for a suspender clasp or similar article, as shown.

MICHAEL GLASER.
